PRESS FOR SOLING SHOES

Erik Algot Hammarsjö, Stockholm, Sweden

Application July 28, 1932, Serial No. 625,442
In Sweden May 18, 1931

19 Claims. (Cl. 12—33)

The old practice of sewing or pegging shoes is fast being discarded in favor of cementing because of the advantages offered by this new method. Cementing is usually done by spreading the cement on the sole and then applying the sole to the insole of the shoe into which a last or like support has been previously inserted, and subjecting the shoe to pressure in a press for soling shoes, the sole being pressed against the insole long enough for the cement to dry.

The only serious drawback to the cementing method has been the difficulty of getting the sole pressed tightly against that part of the shoe known as the welt, and this is particularly true in the half-soling of old shoes. The point is that the welt had a tendency to curl or bend upwardly away from the edges of the sole and the result was that the welt took a wavy form and would be fastened only here and there to the edges of the sole. It is, therefore, the principal object of my invention to provide welt clamps which may be easily and quickly adjusted to the shoe to hold the relatively thin welt portion flat and in firm engagement with the edges of the sole and apply pressure thereon from above to counteract the curling or bending tendency due to pressure from below. A special feature lies in the combination of these clamps with the press parts so that there is proper coordination in the application of pressure to the welt with the application of pressure to the shoe as a whole.

The invention is hereinafter more fully described by reference to the accompanying drawings, in which—

Figure 1 is a vertical section through a shoe press showing welt clamps made in accordance with my invention, the section being on the broken line 1—1 of Fig. 2;

Fig. 2 is a front view of the press, further illustrating the welt clamps;

Fig. 3 is a plan view, and

Figs. 4, 5, and 6 are side, front, and top views, respectively, of the welt clamps removed from the shoe.

The same reference numerals are applied to corresponding parts throughout the views.

Referring to Figs. 1 to 3, the press illustrated comprises an arch or yoke 1 reaching over the base which may or may not be suitably secured to a support. A base-plate 2, adjustable forwardly and rearwardly with respect to the arch, carries two cushions 3, one for each of a pair of shoes to be cemented. The cushions 3 are preferably of hollow rubber construction, filled with

water, and are adapted to have the sole portion of a shoe, indicated at 4, placed thereon for the application of pressure to the sole 5, it being understood that the sole is, of course, treated with cement before it is applied to the shoe. A last, indicated at 6, is put in the shoe covering substantially the entire bottom of the inside of the shoe. On this last is placed a presser foot 7, and pressure is applied to the last through the medium of the foot 7 by a screw 8 threaded in the arch 1. Naturally, in this application of pressure to the shoe, the sole 5 is brought into solid engagement with the insole of the shoe throughout the entire area thereof. The fact that the welt portion 9 of the shoe projects marginally from the shoe and the cushion 3 yields under the application of pressure by the shoe results in the curling or bending upwardly of the welt, when nothing is provided to apply pressure thereto in a fashion corresponding to the application of pressure to the shoe bottom by the last 6. The welt clamps 10 of my invention are provided for the purpose of applying pressure to the welt to hold it flat and in firm engagement with the edges of the sole so that the sole is united to the welt just as securely as it is to any other part of the insole.

As shown in Figs. 4 to 6, the welt clamps 10 are provided in a pair, one for engagement with the welt at the outer side of the shoe and the other at the inner side. Being made of thin sheet metal, they are flexible enough length-wise to be easily conformed to the shape of the shoe. Two rods 11, parallel to one another, provide adjustable spacing and connecting means for the clamps. Each of these rods has an end portion 12 bent downwardly at right angles and entered in registering holes in the opposite sides of the channel-shaped upper end portions 13 of the clamps, as shown in Fig. 5, for a pivotal connection. The other end of each rod is straight and projects through a hole in an inwardly inclined projecting lug on the portion 13 of the companion clamp for a sliding frictional connection with the latter. In other words, each of the rods 11 has a pivotal connection at one end with one clamp and a sliding frictional connection near the other end with the other clamp. The fact that that portion of the clamp through which the straight end of the rod is inserted is bent inwardly causes the clamps to be locked releasably against movement away from one another when they have been pushed in against the sides of the shoe. Each clamp has inwardly projecting teeth 14 formed on the lower edge thereof for engagement

with the welt to press the same into firm engagement with the marginal edges of the sole. The advantage of having teeth instead of a continuous flange lies in the fact that the clamps are 5 more easily flexed to conform to the shape of the shoe.

In operation, the clamps are adjusted with respect to one another to bring the teeth 14 into engagement with the welt along both sides of the 10 shoe, and the operator is careful to have the cross- rods 11 arranged so that they will be forced downwardly by the presser foot 7 at the same time that the presser foot applies pressure to the last 6 to force the shoe down upon the cushion 3. 15 In that way, there is every assurance that the welt 9 will be kept flat and in firm engagement with the marginal portions of the sole 5, and the resulting cementing job will be uniformly good and there will be no danger of portions of the welt 20 standing away from the sole.

What I claim is:

1. In a shoe press, the combination of a cushion support whereon to clamp the sole portion of a shoe, a last entered in the shoe for clamping purposes, means for applying clamping pressure to the last, a presser foot operated by the last mentioned means having a lower portion bearing on the last and an upper portion extending from the shoe, and welt clamping means acted upon 30 by the upper portion of the presser foot to force the welt downwardly simultaneously with the application of clamping pressure to the sole portion.

2. In a shoe press, the combination of a cushion support whereon to clamp the sole portion of a shoe, a last entered in the sole portion of the shoe for clamping purposes, means bearing upon the last to apply clamping pressure to the sole portion, means bearing upon the welt of the shoe to 40 apply clamping pressure thereto, and a single screw for simultaneously applying pressure to the sole and welt clamping means.

3. In a shoe press, the combination of a cushion support whereon to clamp the sole portion of a shoe, a last entered in the shoe for clamping purposes, a screw for applying pressure to the last, a presser foot of substantially U-shape having a lower portion bearing on the last and a forwardly projecting upper portion reaching over the toe 50 of the shoe, the aforesaid screw bearing on said upper portion to apply pressure to the last, and one or more welt clamps engaging the welt portion of the shoe and having a part extending transversely with relation to the upper portion of 55 the presser foot and engaging therebeneath, whereby to have the pressure of the screw exerted simultaneously upon the welt clamps and last.

4. In a shoe press, the combination of a cushion support whereon to clamp the sole portion of a shoe, a last entered in the shoe for clamping purposes, a screw for applying pressure to the last, a presser foot of substantially U-shape having a lower portion bearing on the last and a forwardly projecting upper portion reaching over the toe 60 of the shoe, the aforesaid screw bearing on said upper portion to apply pressure to the last, and welt clamping means having engagement with the welt portion along opposite sides of the shoe, and one or more cross-members extending between said clamping means and connected with 65 the latter so as to permit adjustment of the clamping means toward and away from the opposite sides of the shoe, said cross-members engaging beneath the upper portion of the presser foot, whereby to have the pressure of the screw 70

exerted simultaneously upon the last and welt clamping members.

5. A device of the class described comprising a pair of opposed welt clamping members adapted to extend along opposite sides of a shoe in 5 engagement with the welt portion thereof, and a pair of cross-rods for adjusting and holding said members in spaced relationship, one of said rods having pivotal connection with one of said members and the other of said rods having pivotal 10 connection with the other of said members, said rods projecting from the pivots on the respective members laterally toward the other members and having sliding frictional engagement therewith whereby said members are quickly and easily adjustable relative to one another and are releasably held in adjusted position.

6. A device of the class described comprising a pair of opposed welt clamping members disposed substantially vertically on opposite sides 20 of a shoe over the welt portion thereof for applying downward pressure thereon, a cross-rod having a downwardly bent end portion pivoted on one of said members on a vertical axis and having its other end slidably frictionally horizontally 25 in a hole provided in the other member, and a second cross-rod corresponding to the first rod but having its pivotal and sliding connections on the respectively opposite members, whereby said members are adapted for adjustment toward and 30 away from one another and to be held in adjusted position.

7. A device of the class described comprising a pair of substantially vertical sheet metal welt clamps, the upper portion of each clamp being 35 bent to substantially channel shape whereby to provide substantially horizontal opposed flange portions and a substantially vertical connecting portion, the flange portions having registering holes to provide for pivotal connections on vertical 40 axes, each of said upper portions also having an upwardly projecting inwardly inclined lug having a hole provided therein for sliding frictional connections on horizontal axes, and a pair of cross-rods each having a downwardly bent end 45 portion, the end portion of one rod being entered in the registering holes in the one member and the end portion of the other rod being entered in the registering holes of the other member for pivotal connections on vertical axes, the other end 50 of one rod extending horizontally through the hole in the lug on one member and the other end of the other rod extending horizontally through the hole in the lug on the other member for sliding frictional connections, whereby said members are adjustable toward and away from 55 one another and are held releasably in adjusted positions.

8. A device as set forth in claim 7 wherein said clamping members have inwardly bent welt engaging teeth on the lower edges thereof, said teeth being formed and related so as to permit flexing or straightening of said members to conform to different shaped shoes.

9. In a shoe press, the combination of a 65 cushion support whereon to rest the sole portion of a shoe, means engaging the sole portion of the shoe to press the same against the cushion support, said means including welt engaging portions, and a single screw for applying pressure to 70 said means.

10. In a shoe press, the combination of a cushion support whereon to clamp a shoe, opposed welt engaging members on the opposite sides of the shoe to apply downward pressure on 75

the welt to clamp the margins of the sole portion of the shoe on the cushion support, the welt engaging members being adjustably interconnected by cross-members, a last in the shoe, a presser foot 5 slideable on the last and having a portion with an inclined surface arranged over the cross-members to engage the same, and means for applying pressure to said presser foot.

11. In a shoe press, the combination of a cushion support whereon to clamp the sole portion of a shoe, means engaging the shoe internally to apply clamping pressure toward the cushion support, means engaging the welt externally of the shoe to apply clamping pressure toward the cushion support, a screw for applying pressure to one of the last two mentioned means, and means for transmitting pressure therefrom to the other of said means.

12. In a shoe press, the combination of a cushion support whereon to clamp the sole portion of a shoe, means engaging the shoe internally to apply clamping pressure toward the cushion support, means engaging the welt externally of the shoe to apply clamping pressure toward the cushion support, and means for applying pressure to the first mentioned means, including an intermediate pressure transmitting member arranged so as to transmit pressure from the first mentioned means to the second mentioned means.

30 13. A device as set forth in claim 5 wherein said clamping members have inwardly bent welt engaging teeth on the lower edges thereof, said teeth being formed and related so as to permit flexing or straightening of said members to conform to different shaped shoes.

14. A device of the class described comprising a pair of opposed welt clamping members disposed substantially vertically on opposite sides of a shoe over the welt portion thereof for applying downward pressure thereon, a pair of cross-rods each having a downwardly bent end portion having pivotal engagement in one of the clamping members on a vertical axis, and each of said clamping members having an upwardly projecting inwardly inclined lug having a hole provided therein to receive one of said rods for sliding frictional connection on a horizontal axis, whereby the clamping members are adjustable toward and away from one another and are held releasably in adjusted positions.

50 15. A device of the class described, comprising welt clamping means having portions for engagement with the welt portion along opposite sides of a shoe, one or more cross-rods extending between the portions of the clamping means and pivotally connected at one end to the one portion on a vertical axis and arranged to have sliding frictional connection with the other portion of the welt clamping means on a horizontal

axis, and an upwardly projecting inwardly inclined lug on the last named portion of the welt clamping means having a hole provided therein to slidably frictionally receive said rod, whereby said welt clamping means is adjustable toward and away from the opposite sides of the shoe and is held releasably in adjusted positions. 5

16. In a shoe press, the combination of a cushion support whereon to clamp the sole portion of a shoe, a last entered in the shoe for clamping purposes, a screw for applying pressure to the last, a presser foot having a lower portion bearing on the last and an upper portion on which the screw engages, and welt clamping means acted on by the upper portion of the presser 15 foot to force the same downwardly simultaneously with the application of clamping pressure to the sole portion.

17. A device of the character described comprising opposed welt engaging members and 20 cross-bars pivotally and slidably engaged in openings provided therefor in said members, whereby to permit adjustment of the members toward or away from one another and to different angularity with respect to one another, said cross-bars 25 being disposed at a sufficient elevation with respect to the welt engaging portions of said members to be disposed in spaced relation above the toe portion of a shoe engaged by said members.

30 18. In a shoe press comprising a cushion support whereon to clamp the sole portion of a shoe, and means for clamping a shoe thereon, welt clamping means comprising opposed welt engaging members and cross-bars pivotally and 35 slidably engaged in openings provided therefor in said members, whereby to permit adjustment of the members toward or away from one another and to different angularity with respect to one another, said cross-bars 40 being disposed at a sufficient elevation with respect to the welt engaging portions of said members to be disposed in spaced relation above the toe portion of a shoe engaged by said members, and means for applying downward pressure to at least one of 45 said cross-bars, whereby to transmit clamping pressure to the welt portion of the shoe.

19. A device of the character described comprising, in combination, a support adapted to be engaged by the sole portion of a shoe, a screw 50 extending toward said support, a last for clamping a shoe on said support, welt clamping means for clamping the welt of the shoe on said support, and a presser foot actuated by the aforesaid screw and acting directly on the last to apply 55 clamping pressure thereto and also operatively engaging the welt clamping means.

ERIK ALGOT HAMMARSJÖ.
